UNITED STATES PATENT OFFICE

2,631,683

DRAIN VALVE FOR REFRIGERATION CARS

Linton B. Burr, Evansville, Ind., assignor to International Steel Company, Evansville, Ind., a corporation of Indiana

Application December 31, 1948, Serial No. 68,470

1 Claim. (Cl. 182—8)

1

My invention relates broadly to drainage systems for refrigeration cars, and more particularly to an improved construction of drain valve for refrigeration cars.

One of the objects of my invention is to provide a drain valve system for refrigeration car installation by which infiltration of warm air into the refrigeration car is obstructed, while periodic draining of the refrigeration car may be effected.

Another object of my invention is to provide a construction of drain valve which is counterbalanced to normally close the drain opening for preventing infiltration of air into the drain, while permitting discharge of fluid from the drain periodically under the weight of an accumulation of fluid from time to time.

Still another object of my invention is to provide a construction of counterweight drain valve which may be permanently installed in the drain pipe of a refrigeration car for normally preventing infiltration of warm air, while being effective for releasing accumulated waste periodically with minimum infiltration into the refrigeration car.

Other and further objects of my invention reside in the improved construction of automatic closure for refrigeration car drain pipes, as set forth more fully in the specification hereinafter following by reference to the accompanying drawings, in which:

Figure 1 is a vertical sectional view through the end of a refrigeration car installation showing the drain pipe associated therewith, and illustrating the application of the automatic closure for the drain pipe arranged in accordance with my invention, the drain pipe being partially broken away and shown in section for explaining the principle of operation of my invention; Fig. 2 is a horizontal sectional view of the drain pan with the associated drain pipe and the automatic closure of my invention associated therewith, the view being taken substantially on line 2—2 of Fig. 4; Fig. 3 is a transverse sectional view of the drain pan and the associated drain pipe and automatic closure valve associated therewith, the view being taken substantially on line 3—3 of Fig. 2; Fig. 4 is a vertical sectional view of the drain pan, pipe, and automatic closure valve associated therewith, the view being taken substantially on line 4—4 of Fig. 2; Fig. 5 is an enlarged side elevational view taken through the drain pipe partially in section, and showing the automatic closure valve in side elevational view; Fig. 6 is a transverse sectional view of the drain

2

pipe taken substantially on line 6—6 of Fig. 5 and showing in plan view the counterweighted automatic closure valve which is associated with the end of the drain pipe in accordance with my invention, the valve being shown in closed position; Fig. 7 is a vertical sectional view through the end of the drain pipe and showing the drain valve in section, the view being taken substantially on line 7—7 of Fig. 6; Fig. 8 is a vertical sectional view through the drain pipe and drain valve with the automatic closure valve closed; and Fig. 9 is a view similar to the view shown in Fig. 8, but showing the automatic closure valve open under the weight of the accumulated fluid, and discharging the fluid while restricting in large degree any infiltration of warm air into the refrigeration car even during the period of discharge.

Referring to the drawings in more detail, 20 reference character 1 designates a conventional refrigeration car having installed adjacent one end thereof the brine tanks 2, 3, 4 and 5 supplied with brine through the header 6 and connections 7, 8, 9 and 10 leading thereto. The header 25 is connected through a main supply and drain valve connection represented at 11, through which valve control rod 12 extends to a position adjacent the top of the refrigeration car to the manual control device 13 controllable from the outside of the refrigeration car.

30 The floor of the refrigeration car is formed from stainless sheet steel at the level designated at 14, terminating in a position beneath the brine tanks adjacent the end of the car in a drain pan 15 formed from stainless steel. The sides 35 of the drain pan 15 abut against the side walls of the refrigeration car to provide a horizontally extending catch basin for drippings from the refrigeration car.

40 As shown more clearly in Fig. 4, the drain pan is disposed at a lower level than the level of the car floor at 14 and receives the drainage from the floor 14 resulting from condensation or other leakage during operation of the refrigeration car.

45 The end transverse partition 16 of the refrigeration car terminates sufficiently above the stainless steel floor 14 as represented at 17 to allow passage of fluid into the drain pan 15. A vertically depending drain pipe 18 connects to the drain pan 15 and provides a vertically extending column in which fluid may accumulate.

50 The end of the drain pipe is closed by a flat valve plate 19 which extends in a plane normal to the axis of the drain pipe 18 and fits directly against the circular ground peripheral surface

$18a$ of the drain pipe, forming a substantially fluid and gas tight closure for the end of the drain pipe. A bracket 20 is secured to the outside wall of the drain pipe 18 adjacent the end thereof, and has a horizontally extending bore $20a$ in the portion $20b$ thereof, which extends transversely from the drain pipe 18 . The fluid valve plate 19 integrally connects with a weight or mass indicated at 21 . This mass or weight 21 is provided with a central recess 22 therein into which transverse portion $20b$ of bracket 20 extends. A pin 23 extends horizontally through the ears 24 and 25 integrally connected with the weighted mass 21 and through the bore $20a$ in the transverse projection $20b$ of bracket 20 , thus providing a pivotal mounting for the fluid valve 19 . The mass or weight 21 is chosen of such value that this mass or weight gravitationally maintains the fluid valve 19 into substantially fluid and gas tight relation to the ground circular end $18a$ of drain pipe 18 . The ground circular end $18a$ of drain pipe 18 constitutes a limiting stop for the valve plate 19 in one position, while the valve plate 19 is free to be tipped against the effective gravitational force of the weight or mass 21 .

Under normal conditions the valve plate 19 functions as a flap valve in the position shown in Fig. 6, closing the end of drain pipe 18 against the infiltration of warm air into the interior of the refrigeration car. However, as condensate and moisture collects in the refrigeration car and rolls down the floor 14 beneath the end partition 16 through the gap 17 on to the drain pan 15 it fills up in an accumulation of fluid in the vertically depending drain pipe 18 . When the weight of the accumulated fluid represented at 26 in Fig. 8 increases in an amount which overbalances mass or weight 21 , flap valve 19 is displaced angularly as represented at $19'$ in Fig. 9, allowing the accumulation of fluid 26 to discharge as represented at $26'$. The weight or mass 21 immediately moves the flap valve from the position $19'$ to the restored position 19 , as represented in Fig. 8, closing off the end of drain pipe 18 and preventing the infiltration of warm air into the refrigeration car and thus impairing the efficiency of the rate of refrigeration therein. Flap valve 19 is pressure operated only so long as the accumulated fluid overbalances the mass or weight 21 . As soon as the gravitational effect of the mass or weight 21 becomes greater than the weight of the accumulated fluid 26 , the end of the drain pipe 18 is closed and thus prepared to receive a further accumulation of fluid or condensate. The operation of the drain valve is automatic and may occur from time to time during transportation. The flap valve 19 is open for only an infinitesimal period of time and therefore does not permit infiltration of warm air to impair the refrigeration condition within the refrigeration car.

Although I have explained my invention particularly in connection with a refrigeration car, I realize that the valve of my invention has many other applications and I desire that the disclosure herein be considered in the illustrative sense and not as limiting my invention to any particular application.

While I have described my invention in one of its preferred embodiments, I realize that modifications may be made, and I desire that it be

understood that no limitations upon my invention are intended other than may be imposed by the scope of the appended claim.

What I claim as new and desire to secure by Letters Patent of the United States is as follows:

An attachment for the end of a drain pipe comprising a drain pipe terminating in a substantially flat peripheral sealing edge extending in a plane substantially normal to the axis of the pipe, a bracket having a rounded central projection extending laterally from the wall of the pipe in a vertical plane and having opposite flat faces and terminating at its outer periphery in a curved substantially semi-circular surface, and a pair of spaced curved extensions integral therewith and conforming with the external contour of the side wall of said drain pipe, detachable bolt members extending radially through the side wall of the end of said drain pipe and engaging said spaced curved extensions, a relatively flat closure member having a sealing portion on one side adapted to engage the end of said drain pipe and having a substantially polygonally shaped counterweight on the other side, a rounded recess disposed in the central portion of the vertical wall of said counterweight immediately adjacent said flat closure member substantially conforming with the curvature of said rounded central projection on said bracket and a pair of lugs extending on opposite sides of the rounded central projection of said bracket and terminating in spaced relation to the detachable bolt members that engage said spaced curved extensions, a pin extending through said pair of lugs and through the rounded central projection of said bracket for journaling said relatively flat member with respect to the end of said drain pipe, said counterweight normally urging the sealing portion of said relatively flat member into engagement with the end of said drain pipe for preventing infiltration of atmospheric air into the drain pipe and enabling the accumulation of fluid in said drain pipe to be discharged therefrom when the weight of the fluid overcomes the effective mass of the counterweight, the bottom surface of said relatively flat member and said counterweight being substantially coplanar, and the upper surface of said counterweight being substantially coplanar with the top of the pair of spaced curved extensions on said bracket.
